UNITED STATES PATENT OFFICE.

JULIAN KENNEDY, OF PITTSBURG, PENNSYLVANIA.

VALVE.

No. 821,943.

Specification of Letters Patent.

Patented May 29, 1906.

Application filed July 21, 1905. Serial No. 270,632.

To all whom it may concern:

Be it known that I, JULIAN KENNEDY, of Pittsburg, Allegheny county, Pennsylvania, have invented a new and useful Valve, of which the following is a full, clear, and exact description, reference being had to the accompanying drawings, forming part of this specification, in which—

Figure 1 is a vertical section showing a flue of a hot-blast stove provided with my improved valve. Fig. 2 is an elevation of a part of the valve. Fig. 3 is a view similar to Fig. 1, showing a modified construction. Fig. 4 is an elevation of part of the valve shown in Fig. 3.

My invention is an improvement upon the furnace-valve shown and described in Letters Patent No. 767,285, granted to me on August 9, 1904. As stated in the said patent, when spectacle-valves and like edgewise-moving valves have been used on the chimney-flues of hot-blast stoves or furnaces it has been the practice to clamp the periphery of the valve to its seat by bolts. Such constructions are unsatisfactory, because it has been found impossible to prevent the valve when so held from warping out of contact from the seat and leaking. The conditions of use prevent the successful packing of the valve, and the difficulty above mentioned is therefore serious.

My invention is designed to provide a valve which is readily movable and which when seated can be held to its seat with great security.

In the drawings, B B represent the flue leading from a hot-blast stove or furnace, through which the gases pass in the direction of the arrow.

2 2' represent the spectacle-valve, the portion 2 being a disk adapted to close the port when it is seated and the portion 2' being annular and adapted to leave the port unobstructed when it is brought opposite to the seat. These portions are connected by a bridge-piece 3, pivotally mounted on a bolt 4 at the side of the annular valve-seat 5, which, in conjunction with the parallel flange 6 on the flue-casing 7, affords a transverse slot 8 for the edgewise movement of the valve, which can be rotated on the pivot 4, bringing the disk portion 2 or the annular portion 2' opposite to the seat. The flue-casing is held to the valve-seat by bolts 8.

9 is a clamping-stem which is independent of the valve and extends through a threaded

socket 10 in the flue-casing and preferably through a sleeve 11, which extends inwardly therefrom and shields the stem from the hot gases when the valve is open. The end of the stem is directed toward the middle of the valve-port, so that when the valve 2 is brought to its seat the stem may be screwed inwardly, so as to bear at the end against the middle of the valve and to clamp it.

Instead of making the disk of the valve portion 2 integral with its rim I make it of a separate circular piece or disk, which is set within an annular rim 12 or frame constituting part of the valve. It is held yieldingly, preferably by means of a spring-disk 13, which is fixed at the middle to the disk 2 by rivets 14 or otherwise and at its free edge bears against a shoulder on the rim 12. The disk 2 bears against the other side of the rim and is thus held yieldingly in place on the valve margin, so that when the stem 9 is screwed inwardly it will force it against the seat independently of the valve-frame, thus giving much greater flexibility to the valve than it otherwise would have and causing it to fit more tightly against its seat. As shown in Fig. 1, the valve-disk 2 is in position to be seated, but has not yet been forced to its seat by screwing in of the stem 9. The construction is preferably such that the valve-disk 2 is rotary within its inclosing rim or frame, and by shifting it rotatively from time to time accuracy of its bearing on the seat is enhanced.

In the construction shown in Figs. 3 and 4 instead of using a spring-disk 13 for holding the yielding portion of the valve to its frame or rim I employ links 15, which are connected to eyes or projections 16 on the frame at one end and at the other end have eyes 17, which are placed upon hooks 18 on the valve-disk proper. This gives a yielding connection between the valve-disk and the frame or rim of the valve, although not a spring connection, but accomplishes the same purpose as above stated of rendering the seat portion of the valve flexibly independent.

In Fig. 3 I also show the valve provided with a packing-ring 18, which may be made of asbestos or other suitable refractory material. The valve can be shifted rotatively relative to the seat by detaching the links 15, turning the valve a one-third revolution, and then reconnecting the links, or if a greater number of links are employed a less revolution will suffice for this purpose.

Within the scope of my invention as defined in the claims the manner of connecting the valve-disk to the rim or frame may be modified in many ways by those skilled in the art, since

5 What I claim is—

1. A flue having a valve consisting of a frame or rim portion mounted to move edgewise into the flue, and a disk portion having a marginal seat on the frame or rim portion, flexible connections between the two portions and means for forcing the disk portion away from its seat on the frame portion to close the valve; substantially as described.
- 15 2. A valve consisting of a rim portion, and a disk portion having a marginal seat on the rim portion, flexible connections between the two portions arranged to permit independent rotary movement of the disk portion, and means for moving the disk portion to close the valve; substantially as described.
- 20 3. A flue provided with a valve consisting of a circular frame or rim portion mounted to move edgewise into the flue, and a circular disk portion inclosed by the frame portion and having a marginal seat thereon, flexible connections between the two portions, and a stem for forcing the disk portion away from

the rim portion to close the valve; substantially as described.

30 4. A valve having an inclosing frame, a valve portion set on one side of the frame and having a spring-plate bearing on the other side of the frame, and means for forcing the valve to its seat; substantially as described.

35 5. A valve comprising a frame adapted to move edgewise into closing position, a valve portion flexibly connected to the frame, and a movable clamp bearing on the valve portion and adapted to force it to its seat together with a casing supporting said clamp; substantially as described.

40 6. A spectacle-valve comprising a frame having an annular open portion, a second frame having a valve portion flexibly connected thereto, and a movable clamp extending into the flue and adapted to bear upon the middle portion of the flexibly-connected member together with a casing supporting the clamp; substantially as described.

45 In testimony whereof I have hereunto set my hand.

50 JULIAN KENNEDY.
